UNITED STATES PATENT OFFICE.

GOSAKU MIHARA, OF SEATTLE, WASHINGTON.

RAILROAD-SWITCH.

1,208,610.

Specification of Letters Patent. Patented Dec. 12, 1916.

Application filed January 12, 1916. Serial No. 71,800.

To all whom it may concern:

Be it known that I, GOSAKU MIHARA, a subject of the Emperor of Japan, residing at Seattle, in the county of King and State 5 of Washington, have invented a certain new and useful Improvement in Railroad-Switches, of which the following is a specification.

My invention relates to improvements in 10 rail-road switches and more particularly to switch stands of that class which is more commonly employed in rail-road yards of the larger towns, and the object of my invention is to provide a rail-road switch 15 which shall embody simple mechanism whereby it can be actuated with more ease and certainty to move its associated rail-points and secure them at required positions for switching a train than is possible 20 with switches heretofore employed. I accomplish this object by devices illustrated in the accompanying drawings wherein—

Figure 1 is a view in side elevation of a 25 structure embodying my invention; Fig. 2 is a plan view of the same, and Fig. 3 is a view of the same in vertical section on broken line α , α of Fig. 2.

Referring to the drawings, throughout 30 which like reference numerals indicate like parts, 4 and 5 are supporting timbers which preferably consist of extended portions of two rail-road ties of an adjacent rail-road track (not shown) with which my invention is associated, and upon the top surfaces 35 of said timbers 4 and 5 are secured by bolts 6 two iron bars 7 and 8 which are disposed transversely in parallel with each other to extend between and unite said timbers 4 and 5 to form a rigid support for operative parts 40 of my invention.

Two bearing brackets 9 and 10 are disposed to be parallel with and to be spaced from each other to extend from the bar 7 to the bar 8, to the top surfaces of which 45 bars 7 and 8 said brackets 9 and 10 are rigidly secured by bolts 11 and 12 respectively, as more clearly shown in Fig. 2. The corresponding central portions of the bearing brackets 9 and 10 are bent to form upwardly projecting angular portions 13 and 14 respectively, and to the underside of each of said angular portions 13 and 14 is secured as by bolts 15 and 16 respectively, an angular bearing member like the bearing member 55 17, as shown in Fig. 1. The apex of each of

the bearing members, as the bearing member 17, and the under side of the apex portion of each of the angular portions 13 and 14 are shaped to form a round hole within which holes are rotatably disposed the cylindrically formed journals of a square shaft 18, one end of which projects outwardly from the angular portion 14 of the bearing bracket 10 for a distance that adapts it to be associated with a lever 19, which is 60 mounted thereon and which is secured in its position by a set-screw 20, whereby said lever 19 may be swung over from its horizontal position, shown by full lines, to the horizontal position, shown in dotted lines 65 of Fig. 1, thereby to rotatively move the square shaft 18 through an angular distance of 180 degrees. The free end of the lever 19 is heavily weighted by a weight 21 fixed thereon, which weight 21 is provided with 70 integral projections 22 which serve as a handle by which it may be actuated by one's hand.

On the square shaft 18, in a position between the bearing brackets 9 and 10, is 75 mounted a pinion 23 which is provided with a series of nine teeth which extends throughout only a larger portion of its circumference while the remaining portion 24 of its circumference is provided with a set-screw 80 25 which serves to fasten said pinion in its position on said square shaft 18, said pinion 23 being so disposed on said square shaft 18 that said remaining portion 24 is disposed to register with the lever 19. A rack-bar 26 85 is slidably mounted in guides formed on the iron bars 7 and 8 at corresponding points between the brackets 9 and 10 where it registers with the position of said pinion 23 whereby its teeth may engage with the 90 teeth of said pinion 23 thus to adapt it to be moved in a lengthwise direction in response to a rotative movement of said pinion 23, and said rack-bar 26 is slidably confined within said guides by iron straps 95 27, as more clearly shown in Fig. 3. The rack-bar 26 is of such length that it may be moved endwise within its guides for such distance as will permit all of the teeth of the pinion 23 successively to engage with 100 its own teeth, and its end portions 28 and 29 (that project outwardly from the iron bars 7 and 8 respectively) are each bifurcated and provided with a bolt hole whereby either of said end portions 28 and 29 105 110

may be pivotally connected to a link, as link 30, whose other end may be articulated to a connecting rod, as the rod 31, which may be extended to and connected with the associated rail-road switch points not shown; thus adapting the structure to be operatively disposed on either side of said associated rail-road switch points.

Manifestly, in the operation of the devices shown and described, the lever 19 when disposed as shown by full lines in Fig. 1, will, by reason of the heavy weight 21, hold the associated switch points of a rail-road switch rigidly in the desired positions, but if it be required to move said switch points to other positions, then one may swing said lever 19 over to the position indicated by dotted lines in Fig. 1, which act will cause the pinion 23 to move the rack-bar 26 toward the right hand for such distance as will move said switch points to such other desired positions where they will be maintained by the gravity of the weight 21 in an obvious manner.

Changes may be made in the forms, dimensions and arrangement of parts of my

invention without departing from the spirit thereof.

What I claim is:

In a switch stand, the combination with 30 parallel supporting members, and parallel cross bars mounted upon said members, of a pair of spaced supporting brackets mounted upon the cross-bars and having upwardly bent intermediate portions, bearing members carried by said upwardly bent portions of the supporting brackets, a shaft journaled in said bearing members, a weighted lever on one end of said shaft, a pinion on the shaft, and a rack bar 35 40 slidably mounted on the cross-bars and engaged by said pinion, said rack bar adapted for connection at either end with a switch point.

In witness whereof I hereunto subscribe 45 my name this twenty-seventh day of December, A. D., 1915.

GOSAKU MIHARA.

Witnesses:

FRANK WARREN,
O. JOHNSON.
